UNITED STATES PATENT OFFICE.

FRANK B. DUNN, OF CONNEAUT, OHIO.

WIRE-CUT BRICK.

No. 918,980.

Specification of Letters Patent.

Patented April 20, 1909.

Application filed March 13, 1908. Serial No. 420,849.

To all whom it may concern:

Be it known that I, FRANK B. DUNN, a citizen of the United States, residing at Conneaut, in the county of Ashtabula and State 5 of Ohio, have invented certain new and useful Improvements in Wire-Cut Brick; and I do hereby declare the following to be a full, clear, and exact description of the invention, such as will enable others skilled in the art to 10 which it appertains to make and use the same, reference being had to the accompanying drawings, and to the letters of reference marked thereon, forming part of this specification.

15 My invention relates to improvements in wire-cut brick.

Heretofore wire-cut brick have been uniformly cut with their side faces plain, and in order to produce raised surfaces on said side 20 faces it has been necessary to put the brick through a process of repressing, which adds greatly to the cost of production. Brick having raised surfaces on their side faces are considered much superior to flat sided brick, 25 particularly when used for paving, and in that case such raised surfaces retain the sides of the bricks a short distance apart thereby facilitating the filling of the joints between the sides of the brick with suitable 30 material such as cement or asphalt, thereby tying them together so as to form a homogeneous structure, which cannot readily be accomplished by the use of flat-sided brick. To the better accomplish this result I have 35 devised a wire-cut brick which is provided with ribs on one side thereof, and corresponding grooves in the opposite side of the brick, all of which I produce during the operation of wire-cutting of the brick, so that the 40 brick comes from the wire-cutter in a finished condition ready for the dry-house and kiln, as is clearly set forth and described in my pending application for patent filed October 2, 1907, Serial No. 395,584, for an invention 45 in wire-cut brick-cutting mechanism.

The features of my invention are herein-after fully set forth and described, and illus-

trated in the accompanying drawings, in which:

Figure 1 is a view in perspective of my improved wire-cut brick, showing ribs on the side thereof. Fig. 2 is a side view in elevation of a section of my improved brick, showing grooves in the opposite side thereof. Fig. 3 is a plan view of a section of pavement 55 made of my improved wire-cut brick.

In these drawings A is one side of the brick, and *a a* are ribs projecting outwardly from, and extending across the side A thereof, and A' is the opposite side of the brick, and *a' a'* 60 are corresponding grooves therein; the brick being formed with the wire-cut ribs *a a* on one side A, and the wire-cut grooves *a' a'* in the opposite side A' thereof, finished complete during the operation of cutting the 65 brick. The ribs and corresponding grooves in the sides of the brick may however, if desired, be wire-cut longitudinally, across, or diagonally on the side of the brick, with equal facility, therefore I do not desire to confine 70 myself to the exact arrangement of the ribs shown and herein described.

In Fig. 3, I show these wire-cut brick as they appear laid in a pavement with the joints between the side-faces filled with 75 cement B so as to lock the bricks together into a homogeneous pavement.

Having thus shown and described my invention so as to enable others to utilize the same, what I claim as new and desire to secure by Letters-Patent is:

1. As an article of manufacture, a wire-cut brick having wire-cut ribs on the side thereof, substantially as set forth.

2. As an article of manufacture, a wire-cut 85 brick having wire-cut ribs on one side, and wire-cut grooves in the opposite side, substantially as set forth.

In testimony whereof I affix my signature, in presence of two witnesses.

FRANK B. DUNN.
